Primary Examiner—Stacia Cadmus*(74) Attorney, Agent, or Firm*—Garcia-Zamor IP Law; Ruy M. Garcia-Zamor(57) **CLAIM**

The ornamental design for a wheel, as shown and described.

DESCRIPTION

FIG. 1 is a perspective view of a wheel according to a first preferred embodiment of my new design;

FIG. 2 is a front elevational view of the wheel of FIG. 1;

FIG. 3 is a left side elevational view of the wheel of FIG. 1; the right side elevational view of the wheel of FIG. 1 being a mirror image of FIG. 3;

FIG. 4 is a top plan view of the wheel of FIG. 1;

FIG. 5 is a bottom plan view of the wheel of FIG. 1;

FIG. 6 is a rear elevational view of the wheel of FIG. 1;

FIG. 7 is a perspective view of a wheel according to a second preferred embodiment of my new design; and,

FIG. 8 is a front elevational view of the wheel of FIG. 7; Portions of the wheel not shown in FIGS. 7 and 8 are disclaimed as forming no part of the claimed design;

The broken lines in FIGS. 1-8 represent environment and are for illustrative purposes only and do not constitute part of the claimed design.
